DAM CONSTRUCTION

Ralph R. Randell, Washington, D. C.

Application October 5, 1927, Serial No. 224,237

21 Claims. (Cl. 61—30)

My invention relates to improvements in dams and other structures subject to fluid pressure; and the objects of my improvements are (1) to more effectively prevent water or other objectionable fluid from reaching the main body of the dam or other structure; (2) to lessen or prevent hydraulic uplift on the dam or other structure and thereby to lesson the magnitude of the required cross-section and the volume and cost of the dam or other structure and to increase its factor of safety; (3) to lessen or prevent deterioration of the dam or other structure by frost action, solution, or chemical or mechanical change due to the presence of water or other fluid; and (4) to improve the appearance of the dam or other structure by lessening or preventing the formation of efflorescence on its face due to the action of water or other fluid.

Heretofore the baneful and serious conditions of leakage, percolation, uplift, frost action, solution, chemical or mechanical change, deterioration, disintegration, and efflorescence formation, insofar as these are due to water or other fluids reaching dams or other structures of the class described from the reservoir or impounded fluid, or from the foundations, abutments, or surroundings of such dam or other structure, have remained largely uncontrolled due to the fact that efforts at drainage have been limited principally to occasional pipe or well drains which have usually been spaced several feet apart and between which there have remained large areas undrained or imperfectly drained. Water or other harmful fluid reaching the dam or other structure through these areas has produced the serious and detrimental effects referred to above. In place of such occasional drains my invention uses drains which are substantially continuous along two dimensions across the path of leakage or flow. These layer drains, on account of their substantial continuity, effectively prevent the ingress of water or other fluid and the resulting deleterious effects.

My invention consists essentially of the use, in a dam or other structure subject to fluid pressure, of a drain, in this specification and claims called a layer drain, which is substantially continuous along two dimensions cross the path of the expected leakage or flow, and which, over all or a considerable area of its surface, is effectively and more or less uniformly capable of receiving fluid from the adjacent material to be drained. This drain may be of any desired size, shape, thickness, material, posture, and location in the structure. It may be either substantially

open, cellular, or relatively porous, and may consist of porous concrete, porous stone, other porous masonry, sand, gravel, crushed rock, other porous material, concrete or other grillage or cells, air space, or other suitable material or arrangement. It may be of uniform or varying thickness; plane, curved, or warped; and either vertical, horizontal, or inclined at any angle. It may either itself extend to an appropriate outlet or outlets, or it may be connected to such outlet or outlets by open, closed, pipe, well, porous, or other drains. It may be traversed by struts or supporting members transferring stress through or across it, or supporting adjacent parts of the structure. It should be unlined unless a lining is necessary to support it or the back-lying material to be drained, in which case the lining or wall of the drain, which may serve to support either the drain, the back-lying material, or both, should be composed of porous concrete, porous stone, other porous masonry, or other porous material, so that fluid from the back-lying material may reach the drain at substantially all points on its surface or a considerable area thereof, rather than only at occasional points of inlet. If the drain or its lining is of porous concrete, the material may be prepared by any convenient method or methods of producing a large percentage of voids in concrete, such as the use of relatively non-angular, uniform-sized aggregate; little or no sand or fine aggregate; only sufficient cement to produce the required strength; little or no tamping; or otherwise.

An application of my invention to a concrete or other masonry dam is shown in the accompanying drawing, in which—

Figure 1 is a plan of a dam; Fig. 2, a downstream elevation thereof; and Fig. 3, a vertical section thereof on the line 1—1, Figures 1 and 2.

Similar numerals refer to similar parts throughout the several views.

In the drawing, 1 is a comparatively impervious face or water-stop, 2 is a structure supporting the face 1, and 3 is a drain. The face 1 and the supporting structure 2 may be of any appropriate size, shape, thickness, material, and posture. They may be either vertical or inclined, and either of uniform thickness, tapering, arched, or of other shape. The impervious face 1 may be plain or reinforced concrete or cement, stone, other masonry, steel, steel imbedded in cement or concrete, steel imbedded in an asphaltic or other water-proof or water-resistant material, or other suitable material; and it may be either on the outside surface or in the interior of the dam. The supporting

structure 2 may be plain or reinforced concrete or cement, stone, other masonry, or other suitable material. The characteristics of the drain 3 are as set forth above. It may be of such size, 5 shape, and disposition as to fulfill also the functions of the supporting structure 2, thereby merging its identity with that of the supporting structure 2, the latter being therefore eliminated as a separate individual element, and the entire 10 supporting structure 2 acting also as a part of the drain 3. The drain 3 presents a substantially continuous face to water leaking from the reservoir past the face 1, or coming from the adjacent foundations or sidewalls toward the 15 supporting structure 2. All such water is therefore intercepted and removed by the drain 3, and the harmful results referred to above are thereby avoided and the objects of my invention as set forth above attained.

20 My invention may in similar manner be embodied in other types of dams and in other structures of the class described, in which cases the element corresponding to the impervious face 1 may be of plain or reinforced concrete or cement, stone, other masonry, earth, steel, steel imbedded in cement or concrete, steel imbedded in an asphaltic or other water-proof or water-resistant material, wood, or other suitable material; and the element corresponding to the 25 supporting structure 2 may be of plain or reinforced concrete or cement, stone, other masonry, earth, crushed rock, or other suitable material.

I claim:

1. In a dam, the combination of a relatively 35 impervious face, a supporting structure, and a porous layer drain located between and bonded to said face and said structure.
2. In a dam, the combination of a relatively 40 impervious face, a supporting structure, and a porous layer drain located between and bonded to said face and said structure; said drain being adapted to directly drain said face substantially uniformly over its adjacent surface, and to directly drain said structure substantially uniformly 45 over its adjacent surface.
3. In a dam, the combination of a relatively 50 impervious face, a supporting structure, and a porous concrete layer drain located between and bonded to said face and said structure.
4. In a dam, the combination of a relatively 55 impervious face, a supporting structure, and an open layer drain between said face and said structure; the upstream and downstream walls of said drain being bonded to said face and said structure, respectively.
5. In a dam, the combination of a relatively 60 impervious face, a supporting structure, and an open layer drain between said face and said structure; the downstream face of said drain being provided with a porous lining.
6. In a dam, the combination of a relatively 65 impervious face, a supporting structure, and an open layer drain between said face and said structure; the downstream face of said drain being provided with a porous lining adapted to resist the stresses within it by cohesive bond between its constituents.
7. In a dam, the combination of a relatively 70 impervious face, a supporting structure, and an open layer drain between said face and said structure; most of the downstream face of said drain being provided with a porous lining through which it is adapted to directly drain the backlying material substantially uniformly over its adjacent surface.

8. In a dam, the combination of a relatively 80 impervious face, a supporting structure, and an open layer drain between said face and said structure; the downstream face of said drain being lined with porous concrete.

9. In a dam, the combination of a relatively 85 impervious face, a supporting structure, and an open layer drain between said face and said structure; most of the downstream face of said drain being lined with porous concrete through which it is adapted to directly drain the backlying material substantially uniformly over its adjacent surface.

10. In combination with a dam, a porous layer 90 drain located approximately between the foundation and the body thereof and adhesively bonded to the adjacent materials.

11. In combination with a dam, a porous concrete layer drain approximately between the 95 foundation and the body thereof.

12. In combination with a dam, a porous concrete layer drain located approximately between the foundation and the body thereof and adapted to function without hydrostatic pressure materially in excess of that necessary to raise the 100 drainage, substantially without frictional loss of head, to an elevation at the downstream face of the dam sufficient to permit it to flow away therefrom by gravity.

13. In combination with a dam, a porous concrete layer drain located approximately between the 105 foundation and the body thereof and adhesively bonded to the adjacent materials.

14. In combination with a dam, a porous concrete layer drain approximately between the 110 foundation and the body thereof; said drain being adhesively bonded to the adjacent materials, and being adapted to function without hydrostatic pressure materially in excess of that necessary to raise the drainage, substantially without frictional 115 loss of head, to an elevation at the downstream face of the dam sufficient to permit it to flow away therefrom by gravity.

15. In combination with a dam, a porous 120 lined open layer drain approximately between the foundation and the body thereof.

16. In combination with a dam, an open layer 125 drain located approximately between the foundation and the body thereof and provided with a porous concrete lining.

17. In a dam, the combination of a relatively 130 impervious face, a supporting structure, and a layer drain located between and adhesively bonded to said face and said structure.

18. In combination with a dam, a layer drain 135 located approximately between the dam and its foundation and adhesively bonded to the material on each side of it.

19. In combination with a dam, a layer drain approximately between the dam and its foundation, said drain being adhesively bonded to the material on each side of it, and being adapted to function without hydrostatic pressure materially in excess of that necessary to raise the drainage, substantially without frictional loss of head, 140 to an elevation at the downstream face of the dam sufficient to permit it to flow away therefrom by gravity.

20. In combination, a dam adapted to distribute the load carried by it over substantially the 145 entire area of its vertical projection on the earth, and a layer drain insulating the dam from its foundation; each side of said drain being adhesively and substantially continuously bonded to the adjacent materials.
